(57) **CLAIM**

The ornamental design for a weeding device as shown and described.

DESCRIPTION

FIG. 1 is a front perspective view of a weeding device, according to a first embodiment of the present design.

FIG. 2 is a top plan view of the weeding device of FIG. 1.

FIG. 3 is a bottom plan view of the weeding device of FIG. 1.

FIG. 4 is a right-side elevation view of the weeding device of FIG. 1.

FIG. 5 is a left-side elevation view of the weeding device of FIG. 1; and,

FIG. 6 is a rear elevation view of the weeding device of FIG. 1.

Where present, the broken lines shown in the figures depict portions of the weeding device that form no part of the claimed design.
